APPARATUS FOR GUIDING LEAD WIRES TO
BE SOLDERED TO CRYSTALSKarl A. Schmuldt, Emmaus, Pa., assignor to
Western Electric Company, Incorporated, New
York, N. Y., a corporation of New York

Application December 9, 1948, Serial No. 64,386

4 Claims. (Cl. 113—99)

1

This invention relates to apparatus for guiding lead wires to be soldered to crystals and has for its object, the provision of a guiding unit formed of members which may be readily machined to accurate dimensions and easily assembled to form an accurate guiding path for the lead wires.

In the manufacture of electrical units in which quartz crystals or synthetic crystals are to be embodied as important parts thereof, lead wires must be soldered accurately to given portions of the crystals whereby the crystals may function properly in their respective units. The lead wires are of exceedingly small diameters and unless means is provided to accurately guide the lead wires in a path relative to a fixed location for the crystals, the lead wires may not be soldered to the required locations on the crystals. Heretofore, tubular guides as shown in Patent 2,409,615 to T. A. Daniel, have been employed to guide the lead wires relative to the crystals during soldering operations. The tubular guides were difficult to produce in that suitable tubular material with an inner diameter of the desired size was not obtainable, making it necessary to drill rod stock in order to produce an aperture approaching the dimensions desired for guiding the lead wire. This was not completely satisfactory in that subsequent heat treatment of the guide after the drilling operation frequently resulted in variations in the dimensions of the guide affecting the guiding aperture. Furthermore, a circular aperture of a size approaching that of the lead wire to accurately guide the wire resulted in undesirable friction affecting longitudinal advancement of the wire.

In accordance with the aforementioned object, the invention comprises an apparatus for guiding a lead wire in a given path when fed longitudinally to a crystal, to which the leading end of the wire is to be soldered, the apparatus including a guiding unit composed mainly of companion members which, when grouped together to form the unit, have surfaces lying tangential with the path of the lead wire to guide the lead in the path.

In the present embodiment of the invention, four members compose the wire guiding unit, these members being substantially identical in general contour with the exception of the fact that two of the members are longer than the other two providing a shoulder adjacent the path against which the lead wire may be forced by a spring pressed clamp to hold the wire against longitudinal movement. The guiding unit is secured to a holder which is adjustably mounted in a support reciprocable relative to a table supporting the crystal, the reciprocation of which causes longitudinal advancement of the lead wire.

2

Other objects and advantages will be apparent from the following detailed description, when considered in conjunction with the accompanying drawing, wherein

Fig. 1 is an isometric view of the apparatus, a portion thereof being broken away;

Fig. 2 is a fragmentary isometric view of the apparatus illustrating the structure of the members forming the wire guiding unit; and

Fig. 3 is an isometric view of a crystal, after the lead wires have been soldered thereto.

Referring now to the drawing, attention is first directed to a table 10 upon which a crystal 11 is positioned in a predetermined location by the aid of locating elements 12 and 14. A lead wire 15 is to be fed longitudinally to a given spot on the crystal 11 whereby the leading end of the lead wire may be soldered as at 16 thereto.

The apparatus for guiding the leading wire

15 includes a wire guiding unit indicated generally at 18 and composed of four members 19, 20, 21 and 22. These members may be formed of suitable material, preferably hardened steel and are machined to identical cross-sectional dimensions whereby their longest lateral dimensions being identical and equal to the shortest lateral dimensions plus the diameter of the lead wire 15. With this difference in the dimensions of each member when assembled as illustrated in

Fig. 2, a wire guiding aperture 24 square in cross-section and having a known dimension throughout its length which is substantially equal to or minutely greater than the diameter of the lead wire. The lower ends 26 of the members 19 to

25, inclusive, are tapered inwardly whereby the operator may more readily observe the leading end of the wire in the performance of the soldering operation. The members 21 and 22 are of greater length than the members 19 and 20 as shown in Fig. 2, a portion of the member 21 being cut away at 27 to provide a surface 28, the members 21 lying in a plane with a surface 29 of the member 22 which forms the adjacent side of the aperture 24.

40 The unit 18 composed of the members 19 to 22, inclusive, is positioned in a U-shaped mounting element 31 which is secured to a holder 32 by the aid of screws 33. It will be apparent that the legs of the U-shaped element 31 are shorter than the width of the unit 18 whereby the unit 18 may be forced against a surface 35 in a recessed portion 36 of the holder 32 and in this manner be firmly held in a given position relative to the table 10. A reciprocably movable head

38 has the holder 32 mounted thereon, the head being movable between given limits to affect advancement of the lead wire longitudinally through the guiding unit 18 during each operating cycle. The holder 32 has a projection 40 integral therewith supporting a handle 41 which functions in

combination with a clamp 42 when the operator is desirous of moving the clamp out of clamping engagement with the lead wire. A thumb engaging portion 43 of the clamp carries a spring 44 engaging the projection 40 of the holder 32 to normally move the clamp 42 about its pivotal connection 45 with the element 31 to urge its wire engaging portion 46 toward the surface 29 of the member 22 to cause clamping of the lead wire.

During operation of the apparatus, the lead wire 15, extending through the aperture 24 of the unit 18 and held therein by the clamp 42, is moved downwardly until its leading end engages the proper spot on the crystal 11. The lead wire is held in this position for a length of time sufficient to complete the soldering operation and solidification of the solder after which the apparatus will be moved upwardly relative to the lead wire. During relative movement of the apparatus and the lead wire, it will be apparent that the circumference of the lead wire will be engaged at equally spaced lines where the four sides or guiding surfaces of the aperture 24 throughout the length of the guide unit 18 are tangential to the circumference of the wire. These surfaces are made as wear-resisting as possible and are positioned relative to each other as a result of the initial machining of the members 19 to 22, inclusive, whereby the lead wire will be accurately guided in a given path toward a predetermined point or portion of the article or crystal to which the wire is to be secured by soldering.

It will be apparent that should the surfaces defining the aperture 24 become worn through continued use, the unit 18 may be readily disassembled and the members 19 to 22, inclusive, ground to recondition the surfaces forming the aperture 24. During the reconditioning processes, the only requirement necessary to assure the accurate dimension of the wire guiding aperture, is that the difference between the width and thickness of each member equal the dimension desired for the lead wire to be guided.

It is to be understood that the above described arrangements are simply illustrative of the application of the principles of the invention. Numerous other arrangements may be readily devised by those skilled in the art which will embody the principles of the invention and fall within the spirit and scope thereof.

What is claimed is:

1. An apparatus for guiding a round cross-sectional lead wire in a given path when fed longitudinally to a crystal supported in a predetermined position relative to the path and to which the leading end of the wire is to be soldered, the apparatus comprising a guiding unit having members substantially identical in cross-section with one cross-sectional dimension of each member being greater than the other cross-sectional dimension by approximately the diameter of the wire whereby the members when assembled into the unit will form a longitudinal wire guiding aperture through the unit which is square in cross-section and which has a cross-sectional dimension substantially equal to the diameter of the wire, and means to support the unit with the longitudinal wire guiding aperture coincident with the said path.

2. An apparatus for guiding a round cross-sectional lead wire in a given path when fed longitudinally to a crystal supported in a predetermined position relative to the path and to which

the leading end of the wire is to be soldered, the apparatus comprising a guiding unit formed of companion members substantially identical in cross-section with one cross-sectional dimension of each member being greater than the other cross-sectional dimension by approximately the diameter of the wire whereby the members when assembled into the unit form a wire guiding aperture having surfaces lying tangential with the path of the lead wire to guide the lead wire in the said path, means to support the unit with the longitudinal wire guiding aperture coincident with the said path, one of the members of the unit being longer than the other members thereof and including an extended portion of the said surface thereof, and a clamp normally urged against the lead wire to hold it against the extended surface of the longer member of the unit to hold the lead wire against movement.

3. An apparatus for guiding a round cross-sectional lead wire in a given path when fed longitudinally to a crystal supported in a predetermined position relative to the path and to which the leading end of the wire is to be soldered, the apparatus comprising a guiding unit having members substantially identical in cross-section with one cross-sectional dimension of each member being greater than the other cross-sectional dimension by approximately the diameter of the wire whereby the members when assembled into the unit will form a longitudinal wire guiding aperture through the unit which is square in cross-section and which has a cross-sectional dimension substantially equal to the diameter of the wire, a support for the crystal, a reciprocating head to support the unit and move it relative to the crystal to feed the lead wire thereto, and a U-shaped retaining element to partially surround the assembled members forming the guiding unit and secure them in their respective positions to the head.

4. An apparatus for guiding a round cross-sectional wire in a given path when advanced longitudinally to a crystal supported in a predetermined position relative to the path and to which the leading end of the wire is to be soldered, the apparatus comprising four members of like cross-sectional dimensions, one cross-sectional dimension of each member being greater than the other cross-sectional dimension by approximately the diameter of the wire whereby the members when assembled in a given arrangement will form a longitudinal wire guiding aperture which is square in cross-section with the four surfaces lying tangential with the wire, a support for the members, and means to removably secure the members in their assembled relation to the support.
